1 Claim. (Cl. 315—18)

ABSTRACT OF THE DISCLOSURE

A deflection circuit for beam writing display tubes to provide a constant writing rate including an incremental summing means, an amplifier connected to the summing means, a damped oscillatory charging circuit for slow beam deflection in the writing mode and a pair of oppositely polarized diodes in parallel to permit rapid beam deflection when accessing a position from which to trace a line.

This invention relates to a deflection circuit for cathode ray tubes, and more particularly to an incremental positioning circuit which provides a constant writing rate for cathode ray display tubes or computer read-out tubes.

The use of high speed receivers in modern electronic graphic transmission systems has presented the need for better control of electron beam deflection in display devices. This need is acute where the display is a large cathode ray tube, in the order of 16 to 19 inches or more.

The large, high speed cathode ray tubes have, in general, performed well in data processing applications and specifically for such things as the rapid read-out of library data, display of alphanumeric characters and for geographical displays. One of the major drawbacks of these displays has been in instances where the tubes are to provide a visual display which is the subject of high resolution photography.

Formerly circuits utilized for controlling the beam deflection in these tubes increased the voltage to the deflection electrodes sharply. This sharp rise causes an uneven decay in the light energy given off by the phosphor of the tube, and as a result photographs poorly. Before the new and novel circuit of this invention such abrupt voltage changes were necessary because of the speed desired and required when changing the initial writing position of the beam. Prior to this invention there was no way of deflecting the electron beam at a constant rate for writing and also deflecting the beam rapidly for accessing a new position on the face of the tube.

It is, therefore, an object of this invention to provide a circuit for a cathode ray display tube with a constant deflection rate.

It is another object of this invention to provide a cathode ray display tube with a circuit for constant beam deflection but rapid response for changes in initial writing position.

Still another object of this invention is to provide a cathode ray tube circuit with rapid deflection when accessing a position from which to trace a line.

These and other advantages, features and objects of the invention will become more apparent from the following description taken in connection with the illustrative embodiment in the accompanying drawings, wherein:

FIGURE 1 is a schematic diagram of the circuit embodied in this invention; and

FIGURE 2 is a curve illustrating the increase in voltage relative to time provided by the circuit of this invention.

Referring now to FIGURE 1, there is shown generally

a cathode ray display tube 10 with x and y electrostatic deflection plates 12 and 13, respectively. The x and y deflection channels are shown generally at 14 and 16, respectively.

5 In the x deflection channel, which is similar to the y channel, there is shown a well known D.C. computer summing circuit 18. The currents flowing through the resistors R₁, R₂, R₃ . . . R_N in the D/A (digital-analog) network are summed at N and control voltage V_A, the 10 output of amplifier A, in accordance with the following equation:

$$V_A = V_R(R_5) \left(\frac{1}{R_1} + \frac{1}{R_2} + \frac{1}{R_3} + \dots + \frac{1}{R_N} \right)$$

15 where V_R is the reference voltage and R₅ is the feed back resistor.

As the switches (S₁ . . . S_N) in the D/A network open or closed, the step function of the current flow appears at N and causes corresponding abrupt changes in the voltage V_A as shown at 20 in FIGURE 2. The addition of the components C₁, L₁, R₄, D₁ and D₂ change the step function of the voltage developed at V_A to an essentially linear ramp as shown at 22 of FIGURE 2, between T₁ and T₂, the time when the beam is intensified.

The ramp function is the voltage measured across the condenser C₁ in the damped oscillatory charging circuit comprising condenser C₁, inductance L₁ and resistor R₄.

30 The voltages developed across the inductance L₁ for operation in the incremental beam writing mode are smaller than the amount of voltage required to obtain forward resistances in the diodes D₁ and D₂, which are lower in turn than the resistance of R₄. The voltages across L₁ in the beam writing mode are below the knee 35 of the forward I-E characteristic of the diode and in general 0.2 volts.

When accessing a position from which to trace a line, however, large changes in the voltage V_A, are required.

40 Such voltages, in the order of 0.5 volt or more, are needed to cause a greater deflection in the beam, and because of the design purpose of the tube, such changes in voltages must occur rapidly.

These rapid changes in the circuit are accomplished by 45 the switching action of diodes D₁ and D₂. The forward resistances of the diodes under high voltage become substantially less than the impedance of inductance L₁ and resistance R₄ in parallel and hence effectively short circuit the inductor L₁.

50 The output from the x and y deflection channels are fed to the display tube in a normal manner resulting in a constant writing rate, uniform excitation of the cathode ray tube phosphor per unit area, and uniform light energy emission from the phosphor for high resolution photography on the one hand and rapid changes in the electron beam positioning on the other.

Although the invention has been described with reference to a particular embodiment, it will be understood to those skilled in the art that the invention is capable 55 of a variety of alternative embodiments within the spirit and scope of the appended claim.

What is claimed is:

1. An electron beam deflection circuit for display tubes comprising: a means for summing a plurality of currents, consisting of a plurality of serially connected switch and resistor modules connected in parallel; an amplifier means connected to said summing means; a damped oscillatory charging circuit, comprising a capacitor connected serially to and a resistor connected parallel to an inductance, connected between the input to the amplifier and the output of the amplifier; a pair of non-linear impedance devices connected in parallel with said inductance and each

having its easy path of current flow in the opposite direction; and output means coupled to the said damped oscillatory charging circuit and connected to the deflection plates of a display tube, whereby when small voltages are applied to the deflection circuit changes in output are gradual and when large voltages are applied to the circuit the output changes rapidly.
